[57] CLAIM

The ornamental design for a screen for a car/truck, as shown and described.

DESCRIPTION

FIG. 1 is a front elevational view of a screen for a car/truck showing my new design;

FIG. 2 is a front elevational view of the screen of FIG. 1;

FIG. 3 is a side elevational view of the screen of FIG. 1;

FIG. 4 is a top plan view of the screen of FIG. 1.

FIG. 5 is a front elevational view of a second embodiment of the screen for a car/truck showing my new design;

FIG. 6 is a front elevational view of the screen of FIG. 5;

FIG. 7 is a side elevational view of the screen of FIG. 5; and,

FIG. 8 is a top plan view of the screen of FIG. 5.

The broken lines of FIGS. 1 and 5 represent a vehicle and are for illustrative purposes only and form no part of the claimed design. The rear elevational view of the design is not visible in its intended use and is flat.
